(57) **CLAIM**

We claim the ornamental design for a combined multi-head grooming and cleaning tool, as shown and described.

DESCRIPTION

FIG. 1 is a perspective view of our design;

FIG. 2 is a top view thereof, a bottom view thereof being identical to the top view;

FIG. 3 is a right side view thereof;

FIG. 4 is a left side view thereof;

FIG. 5 is a first end view thereof; and,

FIG. 6 is a second end view thereof.

The broken lines in the drawings depict portions of the combined multi-head grooming and cleaning tool that form no part of the claimed design.

1 Claim, 2 Drawing Sheets
